Atty's.

UNITED STATES PATENT OFFICE.

EVAN OWEN WILLIAMS, OF HAMWORTHY, NEAR POOLE, ENGLAND, ASSIGNOR TO
WILLIAMS FOREIGN PATENTS, LIMITED, OF LONDON, ENGLAND.

CONSTRUCTION OF REINFORCED-CONCRETE FLOORS, DECKS, SUCH AS DECKS OF SHIPS, DECK-FLOORS FOR BRIDGES, AND THE LIKE.

1,310,515.

Specification of Letters Patent. Patented July 22, 1919.

Original application filed May 15, 1918, Serial No. 234,764. Divided and this application filed February 8, 1919. Serial No. 275,862.

To all whom it may concern:

Be it known that I, EVAN OWEN WILLIAMS, B. Sc., A. M. I. C. E., a subject of the King of Great Britain, residing at "The Homestead," Hamworthy, near Poole, Dorset, England, have invented certain new and useful Improvements in the Construction of Reinforced-Concrete Floors, Decks, such as Decks of Ships, Deck-Floors for Bridges, and the like, of which the following is a specification.

This invention relates to the construction of reinforced concrete floors, decks, ceilings or the like, and has for its object to facilitate the work connected with such constructions, by the provision of means enabling the molding process thereof to be greatly accelerated and considerably cheapened.

To this end according to this invention use is made in addition to the usual trough shaped molds employed for shaping the slabs and ribs of movable supports arranged in connection with the scaffolding employed in such structures so that while normally supporting the sides of the molds, these supports are capable of being readily displaced at any desired moment in such manner that each individual mold may be instantly freed and removed in downward direction. This enables the molds to be placed and safely to be assembled without having to be nailed or otherwise secured to other parts of the scaffolding, and released without the necessity of removing screw bolts, wedges or the like as will be more clearly seen from the following description of the accompanying drawings, in which:—

Figure 1 represents a vertical cross section through a portion of a reinforced concrete floor and the stiffening ribs or beams thereof and their construction with the aid of trough shaped molds, joists and supporting wings according to this invention.

Figs. 2 and 3 show in sectional and elevational views respectively an arrangement for stiffening the joists when the struts are at some distance apart.

The concrete floor comprises the concrete slab 1 and the usual stiffening ribs or beams 2. Non-collapsible trough shaped molds 3 of wood, metal or other suitable materials are employed jointly with joists 4 and ro-

tatable supports or wings 5. The upright sides of the molds are used for molding the sides of the beams and the horizontal and uppermost surfaces are employed for molding the soffits of the slabs. The upright sides of the molds are preferably made with a slight inward taper from bottom to top. Struts 7 are first erected and the joists 4 are placed on top and the supporting wings 5 which are connected to the joists by bolts 6 are rotated and secured in the position shown in Fig. 1 on the left so as to form lateral projections or supporting shoulders for the upright side of the troughs 3. These troughs are then placed so as to rest on the wings 5 after which the concreting of the slab 1 and of the beams 2 can be effected. As usual in reinforced concrete constructions of this kind it is the practice to strip the centering or molds after a certain interval before actually removing the supports from the undersides of the beams.

With the arrangement above described when the molds 3 are to be removed the bolts 6 are loosened and the wings 5 rotated through 90° to the position shown in Fig. 1 on the right so that the sides of the wings 5 are flush with the sides of the joists 4. The molds 3 are thus clear of their supports and may be removed in downward direction which is assisted by the tapering sides of the molds. The joists 4 may thus be left in position to support the beams 2 formed for any period considered necessary. Where the struts 7 are at some distance apart, it is advisable to stiffen the joists 4 and to this end use is preferably made of a web or board 8, as shown in Figs. 2 and 3. This web 8 is well secured under the joists 4, for instance, in slots in the struts 7, and in order to accommodate the wings 5 slots 9 are provided in the web, as shown.

This case is a division of application No. 234,764, filed May 15, 1918.

What I claim and desire to secure by Letters Patent is:—

1. In apparatus for building concrete structures, the combination of molds having downwardly extending walls spaced apart, joists located in the spaces between said walls, means permanently carried by the joists, and normally extending beyond

the sides thereof to support the molds and being movable relative to the joists while maintaining connection therewith to clear from under the molds for their downward removal, substantially as described.

5 2. In apparatus for building concrete structures, molds having downwardly extending walls spaced apart, joists located in the spaces between the walls to support the 10 ribs of the slab, rotatable supports mounted on the joists and in one position supporting the molds and in another position clearing from beneath the molds to allow their downward removal, substantially as described.

15 3. In apparatus for building concrete structures the combination of molds, joists to fit between the molds, means carried by the joists to support the molds, said means being movable to clear from beneath the 20 molds for their downward removal, struts supporting the joists and supporting boards carried by the struts and extending under the joists, said supporting boards having recesses for the accommodation of the movable 25 mold supporting means of the joists, substantially as described.

4. In apparatus for building concrete structures, molds having downwardly extending walls and spaced apart, joists located in the spaces between the walls to support the ribs of the concrete slabs and mem- 30

bers supported from and below the joists and turnable about vertical axes, said members when turned to positions transversely of the joists extending beyond the sides 35 thereof to afford supports for the molds and when turned through an angle of 90° lying below the joists and within the vertical planes of the sides thereof to clear the spaces below the edges of the molds for their downward removal, substantially as described.

40 5. In apparatus for building concrete structures, molds having downwardly extending walls and spaced apart, joists located in the spaces between the said walls 45 to support the ribs of the concrete slabs and members hung below the lower faces and supported from the joists and extending transversely of the joists and beyond the sides thereof to afford bearings for the lower 50 edges of the walls of the molds, said members being movable from the said transverse position to clear the space below the edge of the mold walls for the removal of the molds downwardly, substantially as de- 55 scribed.

In testimony whereof I have affixed my signature in presence of two witnesses.

EVAN OWEN WILLIAMS.
